CLAIM

The ornamental design for a disk drive, as shown and described.

DESCRIPTION

FIG. 1 is a top, front, right side perspective view of the disk drive showing our new design;

FIG. 2 is a right rear perspective view thereof;

FIG. 3 is a front elevational view thereof on an enlarged scale;

FIG. 4 is a right side elevational view thereof on an enlarged scale.

The left side of the design is identical to the right side.

FIG. 1

FIG. 2

FIG. 3

FIG. 4
